UNITED STATES PATENT OFFICE.

WILLIAM O. ASHLOCK AND HENRY H. ASHLOCK, OF SAN DIEGO, CALIFORNIA.

HEATER FOR AUTOMOBILES.

1,095,976.

Specification of Letters Patent.

Patented May 5, 1914.

Application filed January 4, 1912. Serial No. 669,372.

To all whom it may concern:

Be it known that we, WILLIAM O. ASHLOCK and HENRY H. ASHLOCK, citizens of the United States, residing at San Diego, in 5 the county of San Diego, State of California, have invented a new and useful Heater for Automobiles, of which the following is a specification.

This invention relates to heaters for automobiles, its principal object being to utilize 10 the waste heat radiating from the exhaust pipes of the motor, for the purpose of heating the interior of the tonneau.

A further object is to provide means 15 whereby the flow of the heating medium into the tonneau may be controlled.

A further object is to mount the heater 20 detachably so that the same can be easily applied to or removed from the exhaust pipes of motor vehicles already in use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a side elevation of the attachment in position, the heat conducting pipes being shown in section. Fig. 2 is an end elevation of the attachment. Fig. 3 is a section on line A—B Fig. 1.

Referring to the figures by characters of 40 reference C designates a motor of the ordinary type and from which extend exhaust pipes D opening into a manifold E to which the muffler F is connected.

The tonneau of the car is adapted to 45 be provided, at suitable points, with registers or radiators, not shown, and a heat conducting pipe 1 extends to each of these registers or radiators from a main pipe 2 preferably arranged under the floor of 50 the tonneau although it is to be understood that the same can be disposed wherever desired. Each of the pipes 1 has a valve or damper 3 for controlling the flow of the heating medium through the 55 pipe and one end of the main pipe 2 is open and has a valve 4 whereby said end

can be closed or opened as desired for the purpose of controlling the passage of the heating medium through the pipes. A flange 5 is formed on the other end portion 60 of the main pipe 2 and is adapted to be coupled, detachably, to the heating attachment constituting the main portion of the present invention. This heater consists of two oppositely disposed hingedly connected casing 65 sections 6 adapted to fit snugly around the exhaust pipes D close to the motor C and also to fit snugly around the projecting end portion of the manifold E so as to thus form an air space around the manifold and 70 the exhaust pipes. An inlet opening 7 is formed at the front end of the casing and has a funnel-like wall 8 for directing air into the opening 7. An outlet pipe 9 extends from the back end of the casing and 75 is adapted to be coupled to the flange 5. The inlet 7 is arranged back of and close to the edge of cooling fan G and the circulation of air set up by this fan and also caused by the forward movement of the car 80 will cause air to enter the opening 7 and flow around the manifold E and the exhaust pipes D. The air will thus be thoroughly heated and will pass outwardly through pipe 9 into the main pipe 2. If the valve 4 85 is open the heated air will pass out the rear end of the pipe. If, however, the valve 4 is closed, the heated air will flow outwardly, through the pipes 1 and into the registers or radiators, not shown, the flow of the heating medium through the pipes 1 being controlled by the pipes or dampers 3.

Importance is attached to the fact that the heater constituting the present invention can be quickly applied to ordinary motors 95 simply by swinging apart the casing sections and positioning them at opposite sides of the manifold and exhaust pipes after which the sections can be moved toward each other and secured by means of bolts 10 100 extending through ears 11 or the like projecting from the upper or free edges of the casing sections 6. The pipe 9 is preferably formed in two pieces hingedly connected, one section of the pipe being movable with 105 each section of the casing 6. It is to be understood, however, that if preferred the pipe 9 can be extended from only one of the sections of the casing 6, in which case it will not be necessary to form the pipe in 110 two pieces. The funnel-like wall 8 of the inlet opening 7 is also preferably formed of

2
two parts connected to the respective casing sections but it is to be understood, likewise, that this inlet opening can be formed solely with one of the sections of the casing, in which event it will not be necessary to form the wall of the opening in two parts.

While the device is primarily designed as an attachment to be placed upon motors already in use, it is to be understood, that if desired, the device can be formed upon the motor at the factory, in which event, the attachment need not be detachable although it is to be understood that the detachability of the device is an important feature inasmuch as said device can be removed during hot weather.

It is to be understood that the attachment constituting the present invention is preferably to be covered with asbestos or other 20 heat non-conducting material such as shown at 12 in Fig. 3.

What is claimed is:—

The combination with a motor having a manifold, of a casing made up of opposed

connected sections, one of said sections being insertible between the manifold and the cylinders of the motor and the other section being movable against the manifold and between the tubes thereof, thereby to house the manifold between the sections, means for 25 detachably securing the manifold and sections together, said sections coöperating to form an air inlet at their front ends, an air distributing pipe for directing air into the body of an automobile from the rear end of 30 the casing, said casing being reduced toward the pipe, said casing being adapted to be bodily released and lowered from the manifold in warm weather.

In testimony that we claim the foregoing 40 as our own, we have hereto affixed our signatures in the presence of witnesses.

WILLIAM O. ASHLOCK.

HENRY H. ASHLOCK.
